CLAIM

The ornamental design of a barstool, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by any one of the patent disclosure as it appears in the Patent and Trademark Office patent files or records, but otherwise reserves all copyright and trade dress rights whatsoever.

The nature and intended use is for use as a barstool.

FIG. 1 is a perspective view of a barstool showing my new design.

FIG. 2 is a front elevational view.

FIG. 3 is a left side elevational view. Right side view is identical.

FIG. 4 is a rear elevational view.

FIG. 5 is a top plan view; and,

FIG. 6 is a bottom plan view.
